CLAIM

The ornamental design for a combination computer and briefcase, as shown and described.

DESCRIPTION

FIG. 1 is a right front perspective view showing my new design, in an open position, and with an interior panel partially raised to show the space below it;

FIG. 2 is another right front perspective view thereof showing the interior panel completely raised against the computer screen;

FIG. 3 is a back view thereof;

FIG. 4 is a side view thereof;

FIG. 5 is a right end view thereof the left end view being identical;

FIG. 6 is another side view thereof showing the side opposite the side shown in FIG. 4, and the briefcase in a closed position;

FIG. 7 is a side view thereof with the briefcase shown in an open position; and,

FIG. 8 is a front view thereof.
